UNITED STATES PATENT OFFICE.

LEONARD E. CLAWSON, OF SAN FRANCISCO, CALIFORNIA.

AIR-COOLING DEVICE FOR INTERNAL-COMBUSTION ENGINES.

1,411,410.

Specification of Letters Patent. Patented Apr. 4, 1922.

Application filed April 12, 1920. Serial No. 373,179.

To all whom it may concern:

Be it known that I, LEONARD E. CLAWSON, a citizen of the United States, residing at the city and county of San Francisco and 5 State of California, have invented a new and useful Improvement in Air-Cooling Devices for Internal-Combustion Engines, of which the following is a specification.

This invention relates to an air cooling 10 device for internal combustion engines and especially to means for directing an air blast against the parts of an engine which are subjected to the greatest heat.

One of the objects of the present invention 15 is to provide a simple, cheaply manufactured, easily installed air cooling device for internal combustion engines, especially adapted for automobiles and the like, and particularly to provide a device of the character described which eliminates the use of 20 water cooling attachments, such as radiators, circulating pumps, jackets, etc.

Another object of the invention is to provide a blower adapted to be placed in front 25 of the engine and driven thereby, and in conjunction therewith means for directing the air against the heads, cylinders and other parts of the engine which are subjected to excess heat.

30 Further objects will hereinafter appear.

The invention consists of the parts and the construction, combination and arrangement of parts as hereinafter more fully described and claimed, having reference to the accompanying drawings, in which—

35 Fig. 1 is a side elevation of an internal combustion engine partly broken away, showing the application of the invention.

Fig. 2 is a view of the opposite side of the 40 engine.

Fig. 3 is a cross section of the engine, showing the application of the invention.

Fig. 4 is a detail view of the blower.

Fig. 5 is a detail cross section taken on 45 line 5—5, Fig. 4.

Referring to the drawings in detail, A indicates a standard form of internal combustion engine, 2 the cylinders, 3 the cylinder heads, and 4 the exhaust manifold. 50 Mounted on the front end of the engine is a bracket 5, and journalled therein is a shaft 6, on which is secured a blower 7 and a pulley 8. This pulley is driven by a belt 9 directly from the crank shaft of the engine

and continuous rotation of the blower is thus 55 insured whenever the engine is in operation.

The blower here shown is of the rotary type (see Figs. 4 and 5.), the periphery of the blower being provided with a series of small angularly disposed vanes 10 and a 60 series of larger directing vanes 11. The rotor of the blower is inclosed by a casing 12 and the air delivered thereto by the blower is directed to the several parts of the engine by the tubes shown in Figs. 1, 2 and 3. 65

By referring to the same figures it will be seen that the engine is inclosed by a casing 18. This casing entirely surrounds the engine and is spaced therefrom to form a surrounding chamber. It will also be seen that 70 the upper part of the casing is open to permit a free escape of air delivered thereto. Four pipes, such as indicated at 14, 15, 16 and 17, are connected with one side of the casing as shown in Fig. 1, and another set of 75 pipes, consisting of four in number, as indicated at 19, 20, 21 and 22, similarly form a connection between the blower housing and the opposite side of the casing 18. Each set of tubes directs an air blast against opposite 80 sides of the cylinders and then escapes in an upward direction over the heads and through the opening in the upper part of the casing.

By referring to Fig. 2, it will be seen that 85 another set of pipes, four in number, as indicated at 23, 24, 25 and 26, also form a connection between the blower housing and the casing and that they direct an air blast against the exhaust manifold 4. Two other pipes are employed as shown at 27 and 28. 90 The pipe 28 connects with a manifold 29 and thereby directs an air blast on top of the cylinder heads. Pipe 27 is connected with the lower portion of the jacket, as at 30, and therefore directs an air blast through the 95 jacket space surrounding the cylinders and then upwardly around the heads; the air admitted by the pipes 27 and 28 being permitted to escape through an opening 31, formed at the rear end of the cylinder. 100

The engine shown in this instance is a Ford engine. This type of engine is provided with a jacket 32, which surrounds the cylinders, and similarly a jacket 33 which incloses the heads, the jacket 33 being provided with the manifold 29, through which the circulating water discharges, and the jacket 32 with the opening 30 through which the cool-

ing water is admitted, that is ordinary Ford engines are water cooled, the water being admitted at 30 and discharged through the manifold 29. In the present instance I merely cut away a portion of the jacket 33, at the rear end to form the opening 31, and by directing an air blast through the connections 29 and 30, I force a sufficient volume of cool air through the jacket space to maintain any cylinder temperature desired. Cooling of the engine is of course otherwise materially assisted by the other connections which direct a series of air blasts against the opposite sides of the cylinders as previously described.

From the foregoing it can be seen that a simple air cooling device has been provided for automobile engines which may be attached whether the cylinders are jacketed or otherwise, similarly that all water cooling connections, such as radiators, circulating pumps, etc., may be entirely removed, thereby materially reducing the weight and cost of the engine. Automatic operation is insured due to the fact that the blower cannot operate unless the engine is started and the proportion of air delivered to cool the engine is always proportional to the speed of the same as a direct driving connection is formed between the engine crank shaft and the blower shaft 6. Practically any cylinder temperature desired may in this manner be obtained as the capacity of the blower may be increased or decreased to suit varying conditions or demands. All air employed for cooling purposes is freely liberated once it has been used and a continuous supply of fresh cool air is in this manner constantly surrounding the engine and impinging against the surface exposed to the greatest heat.

An important feature of the invention is the fact that cooling is resorted to by directing an air blast against the part or parts to be cooled. This method of cooling has proven exceedingly efficient when compared with other methods of cooling, and it should therefore be considered an important feature of the present invention.

Another feature to be considered is the fact that back pressure on the exhaust decidedly tends to heat an engine. I therefore provided means for permitting a free escape of the exhaust gases, first by providing a manifold having large passages formed therein, and secondly by providing an auxiliary manifold, such as shown at 4^a. This is connected with the forward end of the main manifold 4 and serves the purpose of bypassing any gases, should there at any time be a tendency to form a back pressure. The manifolds 4 and 4^a may be connected with mufflers if desired, but these should be of ample capacity as back pressure should be avoided as much as possible.

While a specific form of blower is here shown, I wish it understood that any other type suitable for the purpose may be employed; similarly that changes in the piping system and structure here shown may be resorted to within the scope of the appended claims.

Having thus described my invention, what I claim and desire to secure by Letters Patent is—

1. The combination with the cylinders of an internal combustion engine, of an open topped casing surrounding the sides, ends and bottom of the cylinder space, a rotary blower with a surrounding casing, a plurality of tubes connecting the blower casing with the engine casing and discharging at opposite sides of the engine cylinders, a second set of pipes discharging air from the blower casing to and around the exhaust manifold, and a final set of pipes connecting the blower casing with the space on the top of the cylinder heads, and all of said air blasts passing to and out of the open top of the cylinder casing.

2. The combination with the cylinders and heads of an internal combustion engine, of a casing spaced from but enclosing the same, a plurality of pipes connecting the blower with one side of the casing and directing an air blast against each cylinder, a plurality of pipes connecting the blower with the other side of the casing and directing a series of air blasts against the opposite sides of the cylinders, and other pipes connecting the blower with the engine and directing an air blast against the cylinder heads, the air of said several blasts being permitted to escape through an opening formed in the upper part of the casing.

3. The combination with an internal combustion engine having a jacket formed around the cylinders and the heads, of means for directing an air blast through said jacket space both against the cylinders and the heads, a discharge opening formed in said jackets for the escape of said air, a casing surrounding the cylinders and spaced therefrom, the upper part of said casing being open, and means connected with the opposite sides of the casing for directing a series of air blasts against the opposite sides of the cylinders below the cylinder jacket.

4. The combination with an internal combustion engine having a jacket surrounding the cylinders and the head, of a casing surrounding the cylinders and spaced therefrom, a blower driven by the engine, a casing the surrounding the blower, a pipe connecting the blower with the cylinder head jacket, another pipe connecting the blower with the cylinder jacket, a common discharge opening for the cylinder and head jacket, an exhaust manifold on the engine, a plurality of pipes connected with the blower

directing an air blast against the exhaust pipe, and a plurality of pipes connecting the blower with opposite sides of the casing and directing a series of air blasts against opposite sides of the cylinders, and an opening in the upper part of the casing surrounding the cylinders for the free escape of the air.

In testimony whereof I have hereunto set my hand in the presence of two subscribing witnesses.

LEONARD E. CLAWSON.
